(57) **CLAIM**

The ornamental design for an in-vehicle display as shown and described.

DESCRIPTION

FIG. 1 is a perspective view of an in-vehicle display showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the in-vehicle display where the in-vehicle display is in a first configuration of use; and, FIG. 10 is a perspective view of the in-vehicle display where the in-vehicle display is in a second configuration of use.

The short-dash broken lines immediately adjacent to shaded areas represent boundaries of the claimed design. In FIGS. 9–10, the long-dash broken lines showing a car dashboard and the short-dash broken lines showing a dashboard mount illustrate unclaimed environment. All other short-dash broken lines illustrate portions of the in-vehicle display that form no part of the claimed design.
